HANS ARNOLD SCHLAEPFER, OF GENEVA, SWITZERLAND

BOOKKEEPING APPLIANCE

Application filed March 6, 1930, Serial No. 433,712, and in Switzerland April 26, 1929.

This invention relates to a book keeping appliance of the kind of those comprising a supporting member to which are removably secured, a ledger sheet, a journal sheet and a 5 carbon paper interleaved between said two sheets.

It has for its object the provision of a simple easily operated attachment for detachably and adjustably securing the three 10 above mentioned loose sheets to the supporting member.

In the accompanying drawing which illustrates one of the preferred embodiments of my invention,

Fig. 1 is a plan view of the book keeping appliance,

Fig. 2 is a sectional view on the line II—II of Fig. 1,

Fig. 3 is a fragmentary plan view on a 20 larger scale, and

Fig. 4 is a sectional view on the line IV—IV of Fig. 1.

This appliance includes a board 1 made of aluminum. To the left hand side of the 25 board is secured a frame formed of two side members 2, two end members 3 and a median member 4. The right hand side member 2 as well as the median member 4 and the two end members 3 are spaced from the board 1 so as to provide a recess 5 into which may be inserted the journal sheet 6, the carbon sheet 7 and the ledger sheet 8; 9 and 10 refer to two bars adapted to enter the frame on either 35 side of the median member 4. These bars are of unequal lengths and have their bottom face provided with a layer of rubber 15.

One end of the bars is bevelled and adapted 40 to engage a corresponding bevel edge 12 provided on the lower end portion 3 of the frame. Along the opposite side of this frame may be shifted a clip 13, the ends of which slide in 45 two small grooves 14 channelled in the frame. The bar 9 holds the sheet 6 tightly on the board 1 and the bar 10 causes the sheets 7 and 8 to remain in position on the sheet 6. When the clip 3 is placed over the bars as 50 shown in Fig. 1, the three sheets are kept together. When the clip 13 occupies the position as shown in Fig. 3, the bar 10 as well as the sheets 7 and 8 become loose, whilst the

sheet 6 is still maintained in place, so that the sheets 7 and 8, which are slightly shorter than the sheet 6 can be moved along this sheet. For removing the journal sheet 6, the clip 13 has to be pushed to the upper part of the 55 frame 1 until the bars 9 and 10 are cleared.

In illustrating this preferred embodiment of this invention, I want to have it understood that numerous changes and alterations might be made on the general form of the 60 parts described without departing from the said invention and, hence I do not limit myself to the details as set forth, but shall consider myself at liberty to make such changes and alterations as fall within the scope of 65 the appended claims.

I claim:

1. In a book keeping appliance comprising a supporting member adapted to have detachably secured thereto a journal sheet, a 70 ledger sheet and a carbon sheet interleaved between said journal and ledger sheets, a recessed frame secured to one side of the supporting member and comprising side members and a median member, two bars disposed within said frame between said side members and said median member, the journal sheet being adapted to be passed beneath said median member and to be held by one of said bars, the other bar being adapted to 75 hold the ledger sheet and the carbon sheet, said bars each having a bevelled end engaging with a corresponding bevel edge on the frame, and a clip slidably engaged on the frame and adapted to maintain the other end 80 of said bars in the frame.

2. In a book keeping appliance comprising a supporting member adapted to have detachably secured thereto a journal sheet, a 90 ledger sheet and a carbon sheet interleaved between said journal and ledger sheets, a recessed frame secured to one side of the supporting member and comprising side members and a median member, two bars disposed within said frame between said side members and said median member, the journal sheet being adapted to be passed beneath said median member and to be held by one of said bars, the other bar being adapted to hold 95 the ledger sheet and the carbon sheet, said 100

bars each having a bevelled end engaging with a corresponding bevel edge on the frame, and a clip slidably engaged on the frame and adapted to maintain the other end of said bars in the frame, said bars being of unequal length, permitting said clip to engage only the longer or both of the bars.

In testimony whereof I affix my signature.

HANS ARNOLD SCHLAEPFER.
